ELECTRICAL INSULATOR

Andrew Malinovszky, South Gate, Calif.

Application June 8, 1936, Serial No. 84,062

2 Claims. (Cl. 173—366)

This invention relates to electrical insulators, and in particular to concealed strain insulators for high tension electric transmission lines. The object of the invention is to provide an insulator having high mechanical strength combined with high electrical insulating properties. Another object is to provide a strain insulator in which the metallic parts are almost wholly enveloped by the dielectric material, and protected from temperature changes and climatic and corrosive influences. Still another object is to provide a strain insulator in which advantageous dielectric properties and ohmic resistances are maintained during use.

These and other objects are attained by the arrangement and combination of parts shown in the accompanying drawing in which

Fig. 1 is a vertical sectional view of one form of my invention.

Fig. 2 is a plan view of the insulator shown in Fig. 1.

Fig. 3 is a vertical sectional view of another form of my invention.

Fig. 4 is a transverse sectional view taken on the line 4—4 of Fig. 3.

Fig. 5 is an elevation, partly in section, showing another form of my invention.

Fig. 6 is an isometric view of the main ceramic body of Fig. 1.

It is important in high tension insulators that not only should the high insulating value be maintained under all weather conditions, but also that the insulator should have high mechanical strength to resist the strains to which it is subjected in use. It is also important that even under adverse conditions the line should not be allowed to fall to the ground, with consequent danger to life, and the interruption of service. The insulating and dielectric parts of outdoor

insulators are commonly made of vitrified ceramic materials, and it is this type of material which I utilize in my insulator, although I prefer a particular composition discussed below. It is well known that vitrified ceramic materials are much stronger under compressive load than under tension, and I take advantage of this fact in my device. It is also well known that thermal strains, for example from the sun shining on only one side of an insulator, cause mechanical shocks which produce cracks and checks, and ultimately permit moisture to penetrate the body and reduce its insulating value. It is also well known that high temperatures lower the dielectric strength of ceramic insulating material, and that alternating currents cause stresses in a dielectric ma-

terial which will cause further rise of temperature.

In my invention, I use a refractory ceramic composition which when fired at high temperature, has great mechanical strength, high dielectric strength, low coefficient of expansion, low heat conductivity, and high integral and surface ohmic resistance. The material which I have found most satisfactory for this purpose falls within the following composition range.

	Parts per 100
Dumortierite	30 to 70
Ball clay	10 to 20
Kaolin	20 to 30
Tremolite	10 to 30

These materials are ground fine so that they will pass approximately a 150 mesh screen, are then mixed into a slip with water, and the excess water removed by filter-pressing. The articles are then cast, moulded, or formed by the usual methods, and after suitable drying, the shapes are burned to temperatures corresponding to cones 14 to 18. At these temperatures of firing, a natural glaze forms on the surfaces, which makes the pieces impervious to moisture.

Referring to the drawing, Figs. 1 and 2 represent a simple form of my insulator. The main body 11 is cylindrical in shape with the ends recessed for seating the caps 13 and 14, and having two pairs of holes, 15 and 16, and 17 and 18, provided lengthwise of the cylinder body 11 for receiving the legs of U bolts 25 and 26, the curved portion of one U bolt 25 being seated in the recess under the cap at one end of the main body 11, and the curved portion of the other U bolt 26 being seated in the opposite recess. The planes of the two U bolts 25 and 26 are disposed at right angles to each other, with the U opening facing in opposite directions, and in space inter-linked with the porcelain body between them. The end caps 13 and 14 are apertured to allow the legs of the U bolts to protrude, and are so shaped that they substantially fill the recesses at the ends of the ceramic main body 11, and having a protruding portion 27 adapted to fit around the curved portions of the U bolts in the grooves into which said U bolts are seated. The spaces around the U bolts and between the caps 13 and 14 and the main body portion 11, are filled with a suitable cementing material, so that when assembled the insulator is sealed and the internal metal portions protected from weathering and corrosion. Eyelets or hooks or other attaching means are connected to the pro-

truding ends of the U bolts, a connecting plate 28 with attached eyelet 29 between the two legs being shown in the drawing. The ends of the U bolts are threaded for nuts 30 and expansion washers 31 are preferred to take up the differences in thermal expansion of the metal and ceramic parts.

The modification of my invention shown in Figs. 3 and 4 has the main ceramic body 11, with caps 13 and 14, and U bolts 25 and 26, similar to those in Figs. 1 and 2. There is provided, in addition, an outer ceramic cylinder 32 having an air space 42 between it and the main cylindrical body 11, which outer cylinder is held in position by groove 33 in the outer cap 34 and the collar 39 in the lower outside cap 35, fitting over the inner caps 13 and 14. These outer caps 34 and 35 are extended to provide "umbrella" skirts or "petticoats" 36 and 37 for shedding rain and snow, and these skirts are preferably provided with concentric ribs or rings 38 which lengthen the path for surface electrical discharges, or "flash-over" from one metallic part to another. The air insulating space between the outer and the inner cylinders prevents unequal heating of the inner parts, and the outside cylinder and caps also provide protection to the inner cylinder from dust and moisture accumulation. The parts are all held together by the nuts and expansion washers on the U bolt legs. The inner and outer caps may also be made in single pieces.

Another form of my invention is shown in Fig. 5, which is similar in construction to Fig. 1, but having a "petticoat" 36 intermediate the end caps for shedding rain and snow. This "petticoat" is preferably made integral with the main cylinder 11, but may be made separate and attached by well known means.

While I have illustrated and described several modifications of my invention, I do not limit myself to the particular forms shown, but restrict my invention only insofar as necessitated

by the prior art and by the spirit of the appended claims.

I claim:

1. An electrical strain insulator comprising a cylindrical body of ceramic composition adapted to envelope and support in spaced relation two interlinked U bolts and having a portion of its ceramic mass interposed therebetween, said two metallic U bolts having substantially parallel legs interlinked in spaced relation within said cylindrical body, and two end caps of ceramic composition having apertures respectively for each pair of legs of said U bolts, said end caps having integral protruding plugs adapted to seal up the interlocked portions of the U bolts, means including expansion gaskets associated with said U bolts for attaching the caps to the cylindrical body, and attaching means associated with opposing pairs of protruding legs of said U bolts.

2. An electrical strain insulator comprising a cylindrical body of ceramic composition adapted to envelope and support in spaced relation two interlinked U bolts and having a portion of its ceramic mass interposed therebetween, said two metallic U bolts having substantially parallel legs interlinked in spaced relation within said cylindrical body, two end caps of ceramic composition having apertures for the legs of said U bolts, an outer cylinder of ceramic composition spaced away from said cylindrical body, an upper skirted cap of ceramic composition apertured for the legs of one of said U bolts, a lower skirted cap of ceramic composition apertured for the legs of the other of said U bolts, said upper and lower skirted caps being adapted to space said outer cylinder from said inner cylindrical body, means including expansion gaskets associated with the protruding legs of said U bolts for holding the assembly together, and means associated with the respective pairs of legs of the opposing U bolts for supporting said insulator in strain.

ANDREW MALINOVSKY.
